UNITED STATES PATENT OFFICE.

MARCUS C. ROESSLE, OF WASHINGTON, DISTRICT OF COLUMBIA.

DESIGN FOR A BODY FOR COFFEE OR TEA POTS.

SPECIFICATION forming part of Design No. 23,882, dated December 18, 1894.

Application filed November 21, 1894. Serial No. 529,525. Term of patent 14 years.

To all whom it may concern:

Be it known that I, MARCUS C. ROESSLE, a citizen of the United States of America, and a resident of Washington, in the District of Columbia, have invented and produced a new, useful, and original Design for the Body of a Coffee or Tea Pot, of which the following is a specification, reference being had to the accompanying sheet of drawings.

10 Figure 1 of the drawings is a side elevation partly in dotted lines, and Fig. 2 is a top view omitting the parts shown in dotted lines in Fig. 1; the shapes of such parts, so omitted and hereinafter more particularly set forth, 15 being no part of the present design.

This design consists in the shape or configuration of what may be and is hereinafter termed the body of the pot as represented by full lines in the drawings; its principal features being the peculiar abruptly tapering shape of the spout A, and the shape of the rear wardly slanting cylindrical fixed top B above the cylindrical reservoir C which connects said spout and fixed top. The lower line, 1, 20 (Fig. 1) of the spout A is at an angle of about

twenty degrees to the vertical front line, 2, of the reservoir C, while the angle of its top line, 3, is about fifty degrees, and the angle of the top-line, 4, (Fig. 1) of the fixed top B, relatively to the top line, 5, of the reservoir C, is about 30 twenty degrees, while that of the front line, 6, of said fixed top B to an extension of said front line 2 of the reservoir C is about twenty degrees.

The effect of the whole design is an odd but 35 pleasing appearance.

The shape of the lid D, Fig. 1, and that of the handle E, Fig. 1, with its insulators 7, form no part of the present design. They are represented in dotted lines in Fig. 1 to indicate 40 the appearance of a complete pot.

What I claim as new, and desire to patent under this specification, is—

The design for the body of a coffee or tea pot substantially as herein shown and described. 45

MARCUS C. ROESSLE.
